UNITED STATES PATENT OFFICE.

JOHN G. SANDERS, OF MONROE, LOUISIANA.

GRAVITY AUTOMATIC BOILER FEED APPARATUS.

1,129,235.

Specification of Letters Patent. Patented Feb. 23, 1915.

Application filed November 12, 1913. Serial No. 800,612.

To all whom it may concern:

Be it known that I, JOHN G. SANDERS, a citizen of the United States, residing at Monroe, in the parish of Ouachita and State of Louisiana, have invented a new and useful Gravity Automatic Boiler Feed Apparatus; and I do hereby declare the following to be a full, clear, and exact description of the invention, such as will enable others skilled in the art to which it appertains to make and use the same.

This invention relates to the art of boiler feeders, and particularly to a new and useful improved gravity automatic boiler feed apparatus.

One of the objects of the invention is the provision of an apparatus of this character having a system of conduits including valves therein, and means automatically actuated by gravity means, for opening certain of said valves and closing others of said valves and vice versa, for controlling the water feed from any suitable source of supply to a boiler.

In practical fields the details of construction may be subjected to alterations, falling within the scope of what is claimed.

The invention comprises further features and combination of parts, as hereinafter set forth, shown in the drawings and claimed.

In the drawings:—Figure 1 is a plan view of the improved automatic feeder. Fig. 2 is a side elevation of the same. Fig. 3 is an end elevation. Fig. 4 is a sectional view on line 4—4 of Fig. 1. Fig. 5 is a sectional view on line 5—5 of Fig. 1. Fig. 6 is a sectional view on line 6—6 of Fig. 1. Fig. 7 is a horizontal sectional view of a portion of Fig. 1.

Referring more particularly to the drawings, 1 designates a portion of a supply tank having its upper portion open, and extending from the same adjacent the bottom is a pipe 2, which connects to the union 3. Extending from the union 3 are pipes 4, which connect the elbows 5, from which the pipes 6 and 7 extend. These pipes 6 and 7 connect to the valve casings 8 and 9, which are provided with valves 10 and 11 coöperating with the seats 12. The valves 10 and 11 are provided with valve stems 12^a and 13, the upper portions of which are supplied with openings 14 and 15, the purpose of which will appear later.

Short pipes 16 and 17 connect to the valve

casings 8 and 9. The short pipes 16 and 17 connect to the four-way unions 18 and 19. Connected to the ends 20 and 21 of the unions 18 and 19 are short pipes 22 and 23, which in turn connect to the valve casings 24 and 25 having valve seats 26^a, with which the valves 26 and 27 (which are provided with valve stems 28 and 29) coöperate. The upper portions of the valve stems 28 and 29 are provided with openings 30 and 31, the purpose of which will presently appear. Pipes 32 and 33 (which connect to the elbows 34) are connected to the valve casings 24 and 25. Extending from the elbows 34 toward one another and connected to the T-union 35 are pipes 36 and 37. A pipe 38 connects the T-union 35 with the boiler 39, only a portion of which is illustrated. The four-way unions 18 and 19 are in turn connected to additional four-way unions 40 and 41, by the short pipes 42 and 43. One end 44 of the four-way union 40 is connected to the tank or chamber 45 by means of the pipe 46, while the end 47 of the four-way union 41 is connected to the tank or chamber 48 by virtue of the pipe 49.

Mounted in suitable packed bearings 50 of the unions 18 and 19 is a tubular oscillatory trunnion or pipe 51 having a divisional wall 52 substantially centrally disposed. Branching from the trunnion 51 upon each side of the divisional wall or partition 52 is a branch tube 53. Connecting these branch tubes, as shown at 54 are bulb-like bowls 55 and 56. These bowls or receptacles are substantially pear-shaped, and are provided with chambers 57 and 58.

Arranged on the inside of the unions 40 and 41 are smaller unions 59 and 60, to which the pipes or tubes 61 and 62 connect. The pipe 61 terminates on the inside of the chamber 45 adjacent the top, while the pipe 62 likewise extends upon the inside of the tank or chamber 48, terminating adjacent the top thereof. Also connecting the unions 59 and 60 are the pipes or tubes 63, 64 and 65, and 66, 67 and 68. Telescoping into the pipes 63 and 66 are the pipes or tubes 69 and 70, the ends 71 of which extend into the chambers 57 and 58 of the bulbs, and terminate adjacent the outer closed ends of the bulbs. The pipes or tubes 64 and 67 open to the atmosphere up over the top of the open supply tank, while the pipes 65 and 68 extend into the boiler and terminate adjacent

- to or a little above the water line. In this manner the space above the water in the chambers 57 and 58, and the spaces above the water line in the chambers or tanks 45 and 48 are open to the atmosphere when chambers are filling from tank 1, owing to the pipes 64 and 67 opening to the atmosphere, and by reason of such arrangement and such structure the water will readily flow into such chambers from the supply tank, which is disposed at a height considerably above the same.
- The spaces above the water in chambers 57 and 58 and the spaces above the water in chambers or tanks 45 and 48 are open to the space above the water line in boiler, equalizing the pressure in the tanks with the boiler pressure permitting the water to flow readily into the boiler.
- The pipes 64, 65, 67 and 68 are suitably packed as shown at 72, where they enter the unions 40 and 41. The pipes 64, 65, 67 and 68 are provided with valve casings 73, 74, 75 and 76 having valves 77, 78, 79 and 80, which are provided with stems 81, 82, 83 and 84 having openings 85, 86, 87 and 88. Mounted in guides 89 and 90 of the valve casings 8 and 24 and 9 and 25 are slide bars 91 and 92. Also mounted in guides 93 and 94 of the casings 73, 74, 75 and 76 are slide bars 95 and 96 having cam surfaces 97, 98, 99 and 100, which merge into raised portions 101, 102 and 103. These slide bars 95 and 96 are mounted in the openings 85, 86, 87 and 88 of the valve stems 81, 82, 83 and 84, and when these bars 95 and 96 are reciprocated simultaneously, certain of the valves 77, 78, 79 and 80 are opened and others are closed, and vice versa.
- The bars 91 and 92 are provided with cam portions 104, 105, 106 and 107, which merge into the raised portions 108, 109 and 110 of the said bars 91 and 92. These bars 91 and 92 operate or reciprocate in the openings of the valve stems 12 and 28 and 13 and 29, and when these bars 91 and 92 are reciprocated simultaneously, certain of the valves 10, 26, 11 and 27 are opened, and others are closed, and vice versa.
- Movable with the trunnion 51 is a pair of arms 112, the free ends of which are connected at 113 by the rod 114, which is disposed or arranged between the pear-shaped bulbs, the purpose of which will hereafter appear. This rod 114 also connects to the slide bars 91 and 92, and 95 and 96.
- Operation:** Assuming the chambers 57 and 45 are full of water, having been filled from the supply tank by the gravitation of the fluid owing to the valve 10 being open, while the valves 26 and 78, and 11 and 79 are closed as shown in the drawings, the tubular trunnion will start to rock owing to the gravitation of the bulb 55, the weight of which is increased owing to the body or column of water therein. The bulb 55 is shown as having been moved in dotted lines, and as it is in the act of moving, the trunnion is rocked, and owing to the bar 114 being mounted in the arms 112, which are also movable with the trunnion, the bars 91 and 92 and 95 and 96 are reciprocated synchronously, thereby closing the valves 10 and 77 and 27 and 80, which will cut off the supply to the chambers 45 and 55, and allow the water in such chambers to pass into the boiler and opening the valves 26 and 78 and 11 and 79. While the water is passing into the boiler, the chambers 56 and 48 are being filled, owing to the valve 11 being opened. As soon as the chambers 48 and 56 have become filled, and 45 and 57 emptied (as the machine will not move until the lowered chamber has emptied) the weight or gravitation of the bulbs 58 reverses the movement of the trunnion, thereby reversing the action of said valves, so as to allow the chambers 48 and 56 to empty. These operations alternate consecutively as the water in the boiler is consumed. When the valve 78 is closed, the space above the water line in the boiler is closed to the interior of the chambers 45 and 55, and when the valve 79 is closed the inside of the chambers 56 and 48 are closed to the atmosphere. However, when the chamber 55 is being filled and also the chamber 45, the space above the water in such chambers is open to the atmosphere owing to the valve 77 being opened; this is also true when the chambers 48 and 56 are being filled, owing to the valve 79 being opened, and in this manner the water is allowed a free flow.
- The rocking movement of the trunnion in one direction or the other is limited, owing to one or another of the bulbs 55 and 56 coming in contact with one or another of the buffer bars 116 and 117.
- The invention having been set forth, what is claimed as new and useful is:—
- In an automatic boiler feed apparatus, a system of conduits for connection between a source of water supply and the boiler, two sets of valves for controlling the water to the boiler and adapted to be opened and closed alternately, said valves having their stems terminating in forked ends having anti-frictional rollers, a pair of oscillatory bulbs having supplemental chambers into one or another of which the water flows before entering the boiler, slide bars having spaced apart cam portions in their lengths and engaging the forked ends of the valve stems and under the anti-frictional rollers, and upon reciprocatory movements of said slide bars the cam portions act to open and close said valve, a trunnion with which said bulbs are connected and rocked thereby through the gravitation of one or the other, means rockable with the trunnion and hav-

ing connections with the slide bars for simultaneously operating the bars, whereby one set of valves may be synchronously opened with the closing of the other set and vice versa.

2. In an automatic boiler feed apparatus, a system of conduits for connection between a source of water supply and the boiler, two sets of valves for controlling the water to the boiler and adapted to be opened and closed alternately, a pair of oscillatory bulbs having supplemental chambers into one or another of which the water flows before entering the boiler, slide bars having cam portions for opening or closing said valves, and means automatically actuated by the gravitation of one or the other of said bulbs for simultaneously operating said slide bars whereby one set of valves may be synchronously opened with the closing of the other set and vice versa.

3. In an automatic boiler feed apparatus, a system of conduits for connection between a source of water supply and the boiler, two sets of valves for controlling the water to the boiler and adapted to be opened and closed alternately, a pair of oscillatory bulbs having supplemental chambers into one or another of which the water flows before entering the boiler, slide bars having cam portions for opening or closing said valves, a trunnion with which said bulbs are connected and rocked thereby through the gravitation of one or the other, means rockable with the trunnion and having connections with the slide bars for simultaneously operating the bars, whereby one set of valves

may be synchronously opened with the closing of the other set and vice versa.

4. In an automatic boiler feed apparatus, a system of conduits for connection between a source of water supply and the boiler, two sets of valves for controlling the water to the boiler and adapted to be opened and closed alternately, a pair of oscillatory bulbs having supplemental chambers into one or another of which the water flows before entering the boiler, slide bars having cam portions for opening or closing said valves, a trunnion with which said bulbs are connected and rocked thereby through the gravitation of one or the other, means rockable with the trunnion and having connections with the slide bars for simultaneously operating the bars, whereby one set of valves may be synchronously opened with the closing of the other set and vice versa, a second set of chambers each one of which is adapted to fill or empty at the same time one or the other of the first chambers fill or empty, each set of valves including additional valves adapted to be opened or closed synchronously with the other valves of each set for opening the space above the water line in said chambers and the boiler to the atmosphere.

In testimony whereof I have signed my name to this specification in the presence of two subscribing witnesses.

JOHN G. SANDERS.
